UNITED STATES PATENT OFFICE.

HENRY K. HENNIGH, OF NEWCASTLE, INDIANA.

PHOTO-FILM DEVELOPING OR CHANGING BOX.

1,207,036.

Specification of Letters Patent.

Patented Dec. 5, 1916.

Application filed September 30, 1915. Serial No. 53,368.

To all whom it may concern:

Be it known that I, HENRY K. HENNIGH, a citizen of the United States, residing at Newcastle, in the county of Henry and State of Indiana, have invented certain new and useful Improvements in Photo-Film Developing or Changing Boxes, of which the following is a specification.

This invention relates to improvements in boxes for the changing and development of photographic films wherein the top, bottom and all four sides of the box are all made separable from each other to enable them to be separated in the knock-down form of the box, which is the form in which it is shipped and stored and is usually kept except when in use.

The object is to provide separable joints between said parts which will be proof against the passage of light therethrough, and which will be durable and also inexpensive to manufacture.

I accomplish the above, and other objects which will hereinafter appear, by the mechanism illustrated in the accompanying drawing, in which—

Figure 1, is a perspective view of my invention in operative position. Fig. 2 is a top plan view of same with the screen for the eyes of the operator in the flat or knock-down position of said screen. Fig. 3 is a vertical section on the line 3—3 of Fig. 2, with the eye-screen in position for use instead of knocked down, and Fig. 4 is a horizontal section on the line 4—4 of Fig. 3 showing the corner slip-joints.

Like characters of reference indicate like parts throughout the several views of the drawing.

The box is preferably formed out of sheet metal, such for example, as sheet iron or steel, which may be appropriately galvanized, painted, enameled or finished in any suitable manner. The bottom 5, of the box is formed out of single piece of metal with the four edges turned up to form a continuous flange 6. The sides of the box fit into this flange with a vertical packing-strip 7' between the flange and said sides and a horizontal packing 8' between the lower edges of the sides and said bottom 5. This packing will preferably be felt or other suitable material which will insure a joint impervious to the passage of all rays of light.

The four vertical sides 7, 8, 9 and 10, of the box are connected at the four corners by

lock-joints which are made and broken by endwise sliding movements of the parts. The said corner joints are best illustrated in Fig. 4 where it will be noted that the vertical edges of the sides 7 and 9 are bent back outwardly against said members, thence outwardly at right angles for a distance equal to the thickness of the members 8 and 10, thence outwardly again at right angles to a distance beyond the first named bend equal to the thickness of the sheet metal and thence inwardly at right angles. The vertical edges of the sides 8 and 10 are bent inwardly at right angles and the hooks or flanges thus formed are slid endwise into the corresponding angular or locked channels formed by the above described bending operations in the members 7 and 9. These joints are impervious to light and provide easy means for dismembering or uniting the four sides. The four sides after being assembled as described are set within the flanged inclosure of the bottom 5, and will preferably be retained by fasteners 11, here shown as two-leaf hinges, one leaf of which is permanently secured to the flange 6 and the other to the corresponding side 7 or 9, but the pintle 12 of both hinges is removable for the separation of the hinge and separation of said sides from the bottom.

The sides 7 and 9 have hand-holes 13 for the introduction into the box of the operator's hands, as shown in Fig. 1, and these are surrounded by flexible light-proof sleeves 14, 14, contracted at their outer ends by elastic draws 15, which stretch to let the hands and arms through and then contract the sleeves closely against the arms to exclude the light. The sleeves are made several inches long to make the exclusion of light more certain and also to afford freedom of movement of the arms in and out of the box as required in the film developing or changing operations performed therein. The inner ends of the sleeves are fastened to the box by impingement between the latter and metal rings 16, the rings being secured by screws or bolts 17 to provide for easy removal in the repair of the sleeves.

The side 10 is provided with a window 18 which is closed by a colored glass adapted to exclude all light-rays liable to damage the film, and the four sides of the box, 7, 8, 9 and 10, are covered by a lid or top 19, having a depending marginal flange 20 which receives the upper end of the box.

Vertical packing-strips 7' and horizontal ones 8' are used herein the same manner as described for the packing to exclude light between the sides and the bottom of 5 the box.

The lid 19 has a sight-opening closed by a glass 22 of the same character as that in the window 18, and this sight-opening is screened on three sides by a folding screen 10 comprising a middle member 23 which is hinged at one edge to the lid, close to the opening, and two side members 24 and 25 hinged to member 23. The screen as a whole can be flattened out upon the lid 19, in the 15 manner shown in Fig. 2, when the screen is not in use, but by raising the middle member 23 to a substantially vertical position and then swinging the sides 24 and 25 into contact with the edges of the glass in the 20 adjacent window, it is in position for use as shown in Fig. 1. Pins 26 hold the sides 24 and 25 in operative position.

A shutter 27 is hinged inside of the box opposite to, that is, under the sight-opening 25 and glass 22, and is manipulated by the hands of the operator within the box. The window 18 has a curtain 30 fastened to the side 10.

In the operation of my device, the lid 19 30 is removed and the camera to be loaded or unloaded, together with the film-box to or from which the film is to be transferred, are placed within and the lid 19 is replaced. Then the operator introduces his hands 35 through the side openings and sleeves, opens the shutter 27 and removes the curtain 30. By the aid of the light entering through the window 18 the operator can see through the sight opening to perform such operations as 40 are required.

When not in use the box can be dismembered and the separate parts piled and nested together in small space.

While I have described my invention with 45 more or less minuteness as regards details of construction and arrangement and as being embodied in certain precise forms, I do not desire to be limited thereto unduly or any more than is pointed out in the 50 claims. On the contrary, I contemplate all proper changes in form, construction, and arrangement, the omission of immaterial elements and the substitution of equivalents as circumstances may suggest or necessity 55 render expedient.

I claim—

1. A film-box having sides, top and bottom all in separable members, means for making the joints between the members im-

pervious to light, said box having a sight 60 opening in the top and a window in one side both covered with suitably colored material, screen-holding means on opposite sides of the sight opening, a screen section hinged to the box close to an edge of the sight opening 65 which is at right angles to those near which the screen holding means are located, a pair of screen sections hinged to said first section and adapted to be held in operative position by said screen holding means, said 70 box having hand-holes in two of its sides which are at right angles to the one with the window, and flexible light-proof sleeves surrounding the hand-holes and extending externally of the box to envelop the operator's 75 arms with a light-excluding fit.

2. A film-box having sides, top and bottom all in members which are separable from each other, sliding lock joints connecting said side members with each other, 80 formed by bending the vertical edges of one member outwardly against itself, thence out at right angles, thence back at right angles and thence at right angles across the first bend, and by bending the vertical edge of 85 the mating member at right angles to form a hook which is slid endwise into a hook-shaped bend of the first member, said top and bottom members having marginal flanges which telescopically receive said 90 sides in the assembled condition of the latter, packing means to exclude the passage of light through the joints between the sides and the top and bottom of the box, said box having a window opening and a 95 sight opening and means for permitting the introduction of the operator's hands into the box without admitting light.

3. A knock-down film-box having sides, top and bottom all in members which are 100 separable from each other, means for admitting an operator's hands to the interior of the box without admitting light, said box having a window and a sight-opening and a screen adapted to be raised around the sight 105 opening while the box is in use and to be lowered flat against the top of the box at other times, said screen being in a plurality of sections hinged to each other, one of which sections is hinged to the box.

In witness whereof, I have hereunto set my hand and seal at Indianapolis, Indiana, this 13th day of September, A. D. one thousand nine hundred and fifteen.

HENRY K. HENNIGH. [L. S.]
